(57) **CLAIM**

The ornamental design for a voltage stabilizer for ignition coil, as shown and described.

DESCRIPTION

FIG. 1 is a front side perspective view of a voltage stabilizer for ignition coil showing my design;

FIG. 2 is a rear side perspective view of the voltage stabilizer for ignition coil as shown in FIG. 1;

FIG. 3 is a front elevational view of the voltage stabilizer for ignition coil as shown in FIG. 1;

FIG. 4 is a rear elevational view of the voltage stabilizer for ignition coil as shown in FIG. 1;

FIG. 5 is a left side elevational view of the voltage stabilizer for ignition coil as shown in FIG. 1;

FIG. 6 is a right side elevational view of the voltage stabilizer for ignition coil as shown in FIG. 1;

FIG. 7 is a top plan view of the voltage stabilizer for ignition coil as shown in FIG. 1; and,

FIG. 8 is a bottom plan view of the voltage stabilizer for ignition coil as shown in FIG. 1.

The broken lines, shown in the drawings, indicate portions of a voltage stabilizer for ignition coil which form no part of the claimed design.

1 Claim, 8 Drawing Sheets
